UNITED STATES PATENT OFFICE.

WILLIAM FRANKENBERGER, OF LOUISVILLE, KENTUCKY, ASSIGNOR TO STANDARD SANITARY MANUFACTURING COMPANY, A CORPORATION OF NEW JERSEY.

WATER CONTROL FOR FLUSH TANKS.

Application filed March 19, 1925. Serial No. 16,644.

This invention relates to flush tanks and more particularly to a water supply control for such tanks.

Heretofore the usual supply valve for flush tanks, which is automatically operated by the well-known float controlled mechanism, has produced objectionable noises when in operation and a particularly objectionable hissing sound at the time of closing. It has been discovered that such noises are caused by the friction of the full flow of water through the valve during the closing thereof and an object of this invention is to provide a valve for flush tanks of such construction that all friction noises due to closing of the valve will be eliminated.

A still further object is to provide a flush tank having a water control which will operate quietly and efficiently, be cheap to manufacture and rugged in construction.

These and other objects which will be obvious to those skilled in this particular art are accomplished by means of this invention, one embodiment of which is shown for the purposes of illustration in the accompanying drawings in which Figure 1 is a transverse sectional view through a flush tank provided with one form of this invention. Fig. 2 is a sectional view through the center of the supply control valve shown in Fig. 1, with part of the hush tube shown in elevation. Fig. 3 is a view of a part of the supply control valve chamber in section showing the connected end of the refill tube in elevation and Fig. 4 is a transverse sectional view on the line 4—4 of Fig. 1 with certain of the operating elements removed.

The particular embodiment of this invention which has been chosen for the purposes of illustration is shown in conjunction with an ordinary flush tank 5 having a water supply control valve 6 adapted to be automatically operated by the usual float 7 and associated mechanism.

The valve 6 comprises a casing positioned at the top of a supply tube 8 which has the usual valve port 9 formed at the top thereof within a valve chamber 10. A valve body 11 is slidably mounted in a bore 12 formed at the top of the valve chamber in axial alignment with the seat of the valve port 9, and the valve body is adapted to be reciprocated by the float 7 toward and away from the valve seat to open and close the valve, as is well-known in this particular

art. A leather valve seat engaging face 13 is formed on the bottom of the valve body and engages the valve seat so as to form a water-tight joint when the port is closed.

The objectionable hissing noise which is noticeable with the ordinary type of supply valve is caused by the closing of the valve against a full flow of water passing through the valve port during the closing thereof. In order to overcome this objection and to provide a valve construction which will be quiet in operation, I preferably provide the supply tube 8 with a port or orifice 14 below the valve port 9, and axially aligned therewith. A plunger choke or plug 15 which is smaller in diameter than the port 9 is threaded to the lower face of the valve body 11 and extends downwardly through the valve port. The choke is provided with a beveled lower end 16 which extends through the orifice 14 of the supply tube when the valve is in closed position.

The provision of such a choke having a beveled end which cooperates with the orifice 14 constitutes a means for gradually retarding the flow of water through the valve port before the valve body entirely cuts off the water supply and this gradual reduction in the flow prior to actual closing of the valve port eliminates the objectionable noise which has hitherto been caused by the action of the valve body in closing the port while a full flow of water was passing therethrough. The reduction of flow through the port 9 results from the reduction of flow through the port 14 because of the reduced pressure in the chamber between the ports.

Another source of objectionable noise in structures of this type has been the rush of a solid column of water through the hush tube 17 from the valve chamber to the bottom of the flush tank. By providing a suitable form of opening through at least a part of the hush tube, the friction of such a rushing column of water can be reduced so as to eliminate all noise and provide a structure which will operate quietly. In order to accomplish this result, I preferably form a spiral channel 18 adjacent the lower end of the hush tube. Such a channel can be conveniently formed by inserting a worm 19 within the lower end of the tube as shown in Fig. 2. The result of such a device is the provision of a spiral channel of reduced diameter which prevents the rush of a solid

column of water from the valve body into the tank and thereby reduce the friction noises which hitherto accompanied such an operation.

5 A refill tube 20 extends from the valve chamber 6 into the usual overflow tube 21. Hitherto these refill tubes were provided with threaded ends which were attached to the valve chamber by being threaded into a 10 suitable opening formed therein. The formation of threads upon the refill tube, which is of comparatively small gauge, materially weakened it at that point with the result that in assembling the structure, a large loss 15 was sustained through breakage of the refill tubes at their point of connection with the valve chamber. In order to form a more rugged construction and at the same time provide a device which is more easily assembled, I provide a swivel nut 22 which is held on the end of the refill tube by a flange 23. The valve chamber is provided with a bore 24 extending through the wall thereof and through a lug 25 formed on the outside of 25 the valve chamber wall and having threads for engaging the swivel nut 22 by means of which the refill tube is connected to the valve chamber, see Fig. 3. Such a construction provides a rugged structure and enables the 30 adjustment of the refill tube without any strain being applied thereto.

In order to reduce the friction noises by controlling the flow through the refill tube and in order to prevent a surplus of water 35 flowing through the refill tube with the resultant waste, I provide a set screw 26 threaded in a bore 27 communicating with the opening 24 leading from the valve chamber to the refill tube. By properly positioning the regulating screw 26 the amount of 40 water flowing through the refill tube can be accurately controlled so that no surplus water will be passed therethrough. In addition, the rate of flow through the tube can

be accurately controlled so as to eliminate the friction noises thereof, which have hitherto been present.

The usual ball valve 30 is provided for controlling the flow of water from the flush tank to the associated bowl.

What I claim as new and desire to secure by Letters Patent is:

1. A valve for flush tanks having in combination a valve port, a valve seat surrounding said port, a valve body cooperating with said seat to open and close said port, a second port spaced from said first port and means cooperating with said second port for reducing the flow through said port during closing movement of said valve body.

2. A valve for flush tanks having in combination a supply pipe provided with aligned ports, a valve body adapted to open and close one of said ports and a choke carried by said valve body and cooperating with said other port to reduce the flow therethrough during closing movement of said valve body.

3. A valve for flush tanks having in combination a supply pipe provided with aligned ports, a valve body adapted to open and close one of said ports, a choke plug on said valve body extending through the other port and provided with a tapered end cooperating with said other port to reduce the flow through both of said ports during closing movement of said valve body.

4. A valve for flush tanks having in combination a valve port, a valve body for opening and closing said port, a substantially cylindrical choke on said body extending through said port and provided with a tapered end and means cooperating with said end for reducing the flow through the valve prior to closing of said port.

In testimony whereof, I have hereunto 85 subscribed my name this 13th day of March, 1925.

WILLIAM FRANKENBERGER.
